UNITED STATES PATENT OFFICE.

GEORGE D. ROBERTS, OF HARTFORD, CONNECTICUT.

CONDENSER FOR AUTOMOBILE RADIATORS.

Application filed April 9, 1926. Serial No. 100,928.

This invention relates to condensers especially adapted for use in connection with the water cooling systems of automobiles.

Briefly stated, an important object of this invention is to provide a novel form of condenser adapted to be applied to the neck of an automobile radiator so that the vapor which forms as a result of the employment of non-freezing solutions may be effectively 10 condensed and returned to the radiator to avoid the necessity of frequently replenishing the supply of fluid in the radiator.

A further object is to provide a condenser of the character specified which may be employed in connection with standard automobile radiators without changing the construction or design of the same and without marring the appearance of the automobile.

A further and equally important object of 20 the invention is to provide a condenser of the character specified which is of highly simplified construction, durable in use, and cheap to manufacture.

Other objects and advantages will be apparent during the course of the following description.

In the accompanying drawing forming a part of this application and in which like numerals are employed to designate like 30 parts throughout the same,

Figure 1 is a front elevation of the improved condenser applied.

Figure 2 is a vertical sectional view through the improved condenser.

Figure 3 is a horizontal sectional view taken on line 3—3 of Fig. 1.

In the drawing wherein for the purpose of illustration is shown a preferred embodiment of the invention the numeral 5 designates an internally or externally threaded cap of a suitable material and which as 40 shown in the drawing is adapted for attachment to the neck of a conventional automobile radiator.

Figure 2 illustrates that the attaching stem 6 of a body or annulus 7 is extended through the top of the cap 5 and is securely held in place by means of a lock nut 8. Suitable washers may, of course, be employed between 50 the lock nut 8 and the opposed side of the cap. Figure 1 plainly illustrates that the stem 6 may be provided with an annular shoulder to engage the top of the cap 5 and thereby cooperate with the lock nut 8 in holding the annulus 7 in place.

Figure 1 illustrates that a condensing tube

10 of serpentine formation is positioned within the annulus 7 and is provided with an arcuate inlet branch 11 adapted for the reception of that vapor which collects in the neck of the radiator. The inlet branch 11 extends from a point adjacent the end of the stem 6 and lies more or less closely in contact with the inner wall of the annulus 7 and has connection with the serpentine tube 10. The branches of the serpentine tube 10 are all arranged in the same plane and extend at right angles to the path of travel of the vehicle so that the rush of air against the same will effectively condense the vapor therein.

In carrying out the invention the lowermost portion of the serpentine tube is extended below the cap 5 to define an outlet branch 14 by means of which the condensed fluid is returned to the radiator.

Attention is directed to the fact that the terminal of the outlet branch 14 is adapted to be positioned below the level of the water in the radiator so that vapor is prevented from entering the serpentine tube by way of the outlet branch.

The connecting branches of the serpentine tube are confined between and are engaged by flat retaining rings 20 which as shown in Figure 1 are secured to the annulus 7 by 85 fastening devices 22.

As illustrated in Fig. 1 the branches of the serpentine tube are all inclined downwardly so that the products of condensation will not be trapped, but will be permitted to 90 move down easily into the radiator neck.

The appearance of the improved condensing device is not unlike that of the motor meter so common on automobile radiators of to-day. The employment of the retaining rings 20 provides a simple and reliable means for securing the serpentine tube in place and for allowing free access of air to the major portions of the connecting branches of the condensing tube.

The arrangement illustrated provides for the quick and economical assembly of the device and makes it a simple matter to remove the serpentine tube or any part of the device for the purpose of repair or replacement.

In carrying out the invention the stem 6 may be provided with a vent tube 33 to prevent the condenser from becoming air bound and to provide a free outlet in case of abnormal boiling of the contents of the radiator.

Figure 1 illustrates that the lower end of the longitudinal vent tube 33 is internally reduced so that it is partially closed to prevent rush of water up the vent when stopping the car.

Having thus described the invention, what is claimed is:

1. A condenser for automobile radiators comprising a cap adapted for attachment to an automobile radiator neck, a body having a stem connected to said cap, a serpentine tube positioned within the said body and having a plurality of communicating downwardly inclined branches for the passage of fluid, and keeper plates detachably secured to opposite sides of said body and detachably holding said serpentine tube in place.
2. A condenser for automobile radiators comprising a cap adapted for attachment to an automobile radiator neck, a body having a stem connected to said cap, a serpentine tube positioned within the said body and having a plurality of communicating downwardly inclined branches for the passage of

fluid, and keeper plates detachably secured to opposite sides of said body and detachably holding said serpentine tube in place, there being an outlet branch connected to one of the branches of the serpentine tube and adapted to be extended below the level of the water in the radiator.

3. A condenser for use in connection with automobile radiators comprising a cap adapted for attachment to an automobile radiator neck, a body having a stem connected to said body, a serpentine tube arranged within the body and having communicating branches adapted for the passage of fluid, one end portion of said tube being arranged in arcuate formation and extending through said stem to define a vapor inlet, and an outlet connected to the other end of said serpentine tube and adapted to be extended below the level of the water in the radiator.

In testimony whereof I affix my signature.

GEORGE D. ROBERTS.
